US00D980663S

(12) **United States Design Patent** (10) **Patent No.:** **US D980,663 S**
(45) **Date of Patent:** **** Mar. 14, 2023**

(54) **DOMESTIC SODA-WATER PREPARING DEVICE**

(71) Applicant: **SODASTREAM INDUSTRIES LTD.**,
Kfar Saba (IL)

(72) Inventors: **Amit Avigdor**, Kibutz Bahan (IL);
Michael Tsinzovsky, Holon (IL)

(73) Assignee: **SODASTREAM INDUSTRIES LTD.**,
Kfar Saba (IL)

(**) Term: **15 Years**

(21) Appl. No.: **35/513,430**

(22) Filed: **Dec. 16, 2021**

(80) **Hague Agreement Data**

Int. Filing Date: **Dec. 16, 2021**

Int. Reg. No.: **DM/218406**

Int. Reg. Date: **Dec. 16, 2021**

Int. Reg. Pub. Date: **Jan. 28, 2022**

(30) **Foreign Application Priority Data**

Jul. 29, 2021 (IL) IL67387
